UNITED STATES PATENT OFFICE.

ARTHUR S. BOEHM, OF BALTIMORE, MARYLAND.

CHIME SWITCH.

Original application filed October 10, 1921, Serial No. 506,673. Divided and this application filed February 9, 1925. Serial No. 8,046.

To all whom it may concern:

Be it known that I, ARTHUR S. BOEHM, a citizen of the United States, residing at Baltimore and State of Maryland, have invented certain new and useful Improvements in Chime Switches; and I do declare the following to be a full, clear, and exact description of the invention, such as will enable others skilled in the art to which it

10 appertains to make and use the same.

My invention relates to improvements in electric switches designed primarily for controlling electrical church and cathedral chimes, the present application being a division of my U. S. application, Serial No. 15 506,673, filed Oct. 10, 1921.

The principal object is to provide a novel controlling switch for the sounding means of each chime, including two separately 20 movable keys associated with each other in much the same manner as the usual black and white keys of a piano or like instrument, the arrangement being such that when the longer key is depressed, the chime will be 25 sounded loudly while depression of the short key will cut in a resistance and thus softly sound the chime.

Another object is to make novel provision 30 for preventing arcing between the contacts of the controlling switch, when said contacts are separated.

With the foregoing in view, the invention resides in the novel subject matter herein-after described and claimed, the descriptive 35 matter being supplemented by the accompanying drawing.

Figure 1 is a diagrammatic view showing the switch associated with electrical operating means for one of the chime-playing 40 levers of an ordinary console.

Figure 2 is an enlarged longitudinal sectional view through the controlling switch, parts being in elevation.

Figure 3 is a top view of the switch.

Figure 4 is a vertical transverse sectional view as indicated by line 4-4 of Fig. 2.

In the drawing above briefly described, I have illustrated the switch in connection with a means which may be employed for 50 operating one of a series of chimes, but it is to be understood that this arrangement may be duplicated for all of the chimes and the keys of the several switches assembled on a key-board, ten keys being usually sufficient although any suitable number may

be used. It may be further explained that whereas the usual console or chime playing mechanism, is commonly located in a story of the church or the like, near the belfry, the controlling switches of my invention 60 may be located on the main floor, so that much more cooperation may be had between the operator of the chimes and the persons conducting the ceremony, service or the like.

In the drawing, the numeral 1 designates 65 one of the well known playing levers of an ordinary console, which lever is connected by a rope or cable 2 with a clapper 3 of a chime 4. Beneath the lever 1, a solenoid 5 is shown, whose core 6 is connected as at 7 70 with the lever 1. The passage of electrical current (either alternating or direct) through the solenoid 5 and the action of the core are controlled by a key-switch constituting the present invention. This switch 75 is designated in a general way by the reference character 8. The number 9 has reference to a switch base of insulating material from which a bifurcated standard 10 rises, said standard having a pivot bolt 11 upon 80 which relatively long and short keys 12 and 13 respectively, are pivotally mounted. The longer key 12 is formed with a longitudinal recess or slot 14 within which the key 13 is received, so as to not only produce a compact arrangement, but to locate both the "loud and soft" keys in such proximity to each other that they may be selectively used at will.

At one end, the keys 12 and 13 carry adjustable stop screws 15 which are normally held in contact with a stop plate 16 on a support 15^a rising from the base 9, by means of coiled springs 17 connected to the keys and base. These springs serve to normally 95 move the keys in such a manner as to separate the movable contacts 18, carried thereby, from fixed contacts 19 which are secured upon the base 9.

One form of wiring which may be used 100 is shown in diagram, the numeral 20 having reference to a wire which extends from one terminal of the solenoid coil and is in electrical engagement with both of the contacts 18. The numeral 21 designates a wire leading to the other terminal of the solenoid coil, from any appropriate source of electrical supply, a return wire 22 is shown leading from the contact 19 of the relatively long key 12, while a shunt wire 23 leads 110

from the other contact 19 to the wire 22 and is equipped with a resistance coil 24. By this wiring, when the key 12 is depressed, the current travels through the solenoid coil 5 with full force and thereby sounds the chime 4 rather loudly. When the key 13 is depressed however, the current necessarily flows through the resistance 24 so that the core 6 of the solenoid is affected to a smaller 10 degree, with the result that the chime is only softly sounded. This difference in the sound of the chime will always be uniform, which is greatly advantageous over the result produced by the usual hand-operated 15 console.

To "blow" the arc when the contacts 6 are separated, I provide a novel arrangement of parts. Each contact 19 which is in the form of a post rising from the base 9, is 20 provided with a recess 25 extending therethrough, and across this recess, a magnetic core 26 passes, the ends of said core being provided with pole plates 27 disposed on opposite sides of the contact with their upper ends adjacent the engaging surface 25 thereof. A coil 28 surrounds the core 26 and it is by means of this coil that the wire 22 or 23 as the case may be, is connected with its respective contact 19. This arrangement has been found to effectively prevent arcing.

From the foregoing, it will be seen that my invention, regardless of its extreme simplicity, is highly efficient and greatly advantageous over other forms of switches which might be adapted to the same uses, and as excellent results have been obtained from the details disclosed, they may well be followed, but within the scope of the in- 30 35

vention as claimed, numerous minor changes 40 may be made. Furthermore, it will be understood that the switch structure is not restricted to use with chime-controlling circuits, but may have other applications.

I claim:

1. A key switch comprising a base, a standard rising therefrom, a horizontally elongated key whose intermediate portion is disposed adjacent said standard, said key having a longitudinal slot, a relatively short key in said slot having a finger portion extending above the first named key, a pivot passing through the two keys and through the standard, movable contacts on the lower sides of said keys, stationary contacts on the base for co-action with said movable contacts, and means for normally holding said keys at positions in which their contacts are separated from said fixed contacts. 45 50 55

2. A key switch comprising a base, a bifurcated standard rising therefrom, a horizontally elongated key whose intermediate portion is received between the furcations of said standard, said key having a longitudinal slot, a relatively short key in said slot having a finger portion extending above the first named key, a pivot passing through the two keys and through the furcations of said standard, movable contacts on the lower sides of said keys, stationary contacts on the base for co-action with said movable contacts, and means for normally holding said keys at positions in which their contacts are separated from the fixed contacts. 60 65 70 75

In testimony whereof I have hereunto affixed my signature.

ARTHUR S. BOEHM.
